UNITED STATES PATENT OFFICE.

HERMAN SCHMIDT, OF CHICAGO, ILLINOIS.

PEANUT-WARMER.

1,233,922.

Specification of Letters Patent. Patented July 17, 1917.

Application filed September 30, 1912. Serial No. 723,268.

To all whom it may concern:

Be it known that I, HERMAN SCHMIDT, a citizen of the United States, residing at Chicago, in the county of Cook and State of Illinois, have invented a new and useful 5 Peanut-Warmer, of which the following is a specification.

My invention relates to a device for retaining nuts in a warm condition by the use 10 of hot water, the water being heated by a gasoline burner, and the objects of my improvements are, first, to make an attractive and novel display case; second to provide a peep hole for the burner; third, to make a 15 strong and durable gasoline tank; fourth, to make a cheap, attractive and durable device and other features to become apparent from the description to follow.

My invention comprises several good and 20 important features which necessarily make it more marketable than any peanut warmers heretofore placed on the market, as for instance, a display compartment on all sides of the device; a drain for each display 25 compartment; each compartment being accessible; a peep hole for the burner which is covered by transparent material; and the gasoline tank which has the downwardly extending outlet pipe extending a considerable 30 distance up inside the tank where it is secured to the tank to make it more secure.

To describe my invention so that others versed in the art to which it pertains may make and use the same I have illustrated it 35 on the accompanying sheet of drawing forming a part of this specification in which:

Figure 1, is a front elevation of a peanut warmer embodying my invention, and Fig. 2, is a central, vertical sectional view of 40 Fig. 1.

Similar reference characters refer to similar parts throughout.

The fire box 3 is preferably made of galvanized iron and has four sides and the bottom 45 5 and rests on the four angle iron legs. Within the box 3 is the burner 6 which is connected by means of pipe 7 to the tank 8. The pipe 7 extends through the bottom of tank 8, to which it is secured by solder or 50 otherwise, and up along the inner side of the tank to near its top where it is also secured to the tank by solder or otherwise. This means of fastening rigidly secures the pipe 7 to the tank 8 so there is no danger of the said parts becoming separated or by loosening become leaky. The pipe 7 is provided

with a hole 9 just inside the tank 8 through which the gasoline in tank 8 will gravitate into pipe 7 and thence descend to the burner 6. The pipe 7 is provided with the usual 60 regulating valves 10 and 11.

The water receptacle 12 is arranged to fit into the open upper end of the fire box 3 and is provided with the nut receptacle 13 which is provided with the display compartment 65 14. The water receptacle 12 is arranged with its bottom just above the burner 6 and is provided with the handles 15 by means of which it can be lifted out of the box 3 whenever desired.

The upper part of the water receptacle is provided with an outwardly extending annular flange 16 arranged to rest on the upper edge of the fire box 3, and its uppermost portion 17 extends upward and inward on 75 an incline and has its extremity 18 extending vertically. The upper edge of the nut receptacle 13 is formed into a hook 19 which takes onto the edge 18 of the water receptacle 12 and is supported thereby.

The display compartment 14 is formed between the outer rectangular vertically disposed wall 20 and the inner rectangular vertically disposed wall 21 which are made of any desired height. The lower edge of wall 21 fits snugly outside the hook 19 of the nut receptacle 13 and serves as an upward extension of said receptacle 13. The wall 20 is provided with openings covered by glass 22 or other transparent material. The 80 lower edge of the outer wall 20 rests loosely on the upper part 17 of the water receptacle 12 and is only soldered thereto at suitable intervals so as to permit any water, which may find its way into the display compartment 14, to escape between the lower edge of wall 20 and the part 17.

A cover 23 is provided, hinged at 24, to inclose the nut receptacle 13 and the display compartment 14. The usual filling spout 24' 100 and steam escape pipe 25 are provided on the water receptacle 12.

Having thus fully described my invention what I claim as new and desire to secure by Letters Patent of the United States is:—

1. In a device of the class described, the combination of a water receptacle and a nut receptacle, said nut receptacle supported on the water receptacle to be partly immersed in the water and its upper extremity terminating in an inner rectangular vertically disposed wall, an outer rectangular vertically

disposed wall comprising transparent sheets spaced from the inner wall and supported on the upper part of the water receptacle to form a vertically disposed display compartment between the two walls and said outer rectangular vertically disposed wall supported on the water receptacle to form drain openings between the lower edge of said outer wall and its support.

10 2. In a device of the class described, the combination of a water receptacle provided with an upper inclined part and a nut receptacle, said nut receptacle supported on the water receptacle to be partly immersed in the water and its upper extremity terminating in an inner rectangular vertically disposed wall, an outer rectangular vertically disposed wall comprising transparent sheets spaced from the inner wall and supported by and secured to the upper inclined part of the water receptacle to form a vertically disposed display compartment between the two walls and said outer wall supported on the water receptacle in such

manner as to form drain openings between 25 the lower edge of said outer wall and the water receptacle to permit liquid to drain out of the display compartment.

3. In a device of the class described, the combination of a water receptacle, and a nut receptacle, said nut receptacle supported on the water receptacle to be partly immersed in the water and its upper extremity terminating in a rectangular vertically disposed inclosure and an outer vertically disposed inclosure comprising transparent sheets spaced from the inner inclosure to form a vertically disposed display compartment between the two inclosures.

In testimony whereof I have signed my 40 name to this specification in presence of two subscribing witnesses this 5th day of September, 1912, at Chicago, Illinois.

HERMAN SCHMIDT.
